GILBERT D. JONES, OF NEW YORK, N. Y.

Letters Patent No. 60,739, dated January 1, 1867.

IMPROVEMENT IN QUARTZ-MILLS.

The Schedule referred to in these Letters Patent and making part of the same.

TO ALL WHOM IT MAY CONCERN:

Be it known that I, GILBERT D. JONES, of the city, county, and State of New York, have invented a new and improved Grinding-Mill; and I do hereby declare that the following is a full, clear, and exact description thereof, which will enable others skilled in the art to make and use the same, reference being had to the accompanying drawings, forming a part of this specification, in which—

Figure 1 is a vertical section of my invention, taken in the line *x x*, fig. 2.

Figure 2 is a vertical section of the same, taken in the line *y y*, fig. 1.

Figure 3 is a plan or top view of the bed and scrapers pertaining to the same.

Similar letters of reference indicate like parts.

This invention relates to a new and improved grinding-mill, of the kind commonly termed the "Chilian mill," and it consists in having the peripheries of the wheels or rollers of V form, and the bed, on which the wheels or rollers work provided with an annular V groove, for the peripheries of the wheels or rollers to work or run in.

The invention also consists in the employment or use of scrapers, applied to the machine in such a manner that, by a very simple adjustment, the material to be ground may be kept within the path of the wheels or rollers, and when sufficiently ground, discharged from the bed-plate.

By having the peripheries of the wheels or rollers of V form, and working in a corresponding shaped groove in the bed-piece, a cutting or grinding action is obtained, which renders the mill far more efficient in its operation than the original mill of the class specified; and the substance, while being ground, is also kept more within the path of the wheels or rollers.

A represents the bed of the mill, constructed of stone or metal, and having an annular groove, *a*, made in its upper surface, of V form in its transverse section, as shown clearly in figs. 1 and 2. B is a rectangular framing, which rests on the bed, A, and C is a vertical shaft, fitted centrally therein, the lower end of said shaft being stepped centrally in the bed, A, as shown at *b* in fig. 1. This shaft, C, is formed or provided with a vertical oblong loop or opening, *c*, through which a horizontal shaft, D, passes, and E E are two wheels or rollers, placed loosely on said shaft, and retained thereon by hubs, *d*, on the ends of the same. The wheels or rollers, E E, may be constructed of stone or iron, and their peripheries are of V form, corresponding to the shape of the annular groove, *a*, in the bed, A, in which groove the wheels or rollers rotate or work, as will be understood by referring to fig. 1. On the shaft, C, below the loop or opening, *c*, there is keyed a horizontal bar, F, the ends of which are composed of two prongs or arms, *d d'*, as shown clearly in fig. 3. In one of these prongs or arms, *d*, at each end of said bar, there is inserted a vertical arbor, *e*, and to the lower ends of these arbors curved scrapers, *G*, are attached, which, as the wheels or rollers, E E, travel around in the groove, *a*, scrape or throw the substance being ground into the groove *a*. The other prongs or arms have vertical arbors, *H*, passing through them, which arbors, *H*, extend up through arms, *I*, on the shaft, C, and are connected to the outer ends of levers, *J*, on the arms *I*, the inner ends of said levers being connected by pivots to a sliding sleeve, *K*, on the shaft C, which sleeve is raised and lowered by a lever, *L*. Only one arbor, *H*, is shown in the drawings; but as both are alike, and arranged and operated in precisely the same manner, the representation of one only is deemed sufficient. To the lower ends of the arbors, *H* curved scrapers, *M*, are attached, which, when lowered or brought down in contact with the bed, A, have a tendency to scrape or throw off the ground substance from the bed, A. When said scrapers are raised, they are designed to be above the substance being ground, so that they cannot act upon it. These scrapers, *M*, it will be understood, are raised and lowered by actuating the lever, *L*.

The operation is as follows: The shaft, C, is rotated, by the application of power to its upper end, and the scrapers, *M*, are elevated, and the substance to be ground placed in the annular groove, *a*, in the bed, A. The wheels or rollers, E E, operate with a cutting and crushing action, the crushing action being due to the weight or gravity of the wheels or rollers, and the cutting action due to the sharp edge or angle, *a**, formed by the two inclined surfaces of the peripheries of the wheels or rollers working in the V-shaped annular groove, *a*, the edge or angle, *a**, as the wheels or rollers, E, pass around in the groove, *a*, in the path of a circle, working laterally over the corresponding angle, *b**, formed by the two inclined surfaces of the groove, *a*. The scrapers,

G, throw the substance being ground into the groove, α , preventing it from escaping from the bed, A, and when the substance is sufficiently ground, the scrapers, M, are lowered, and said scrapers throw the ground substance from the bed, the scrapers, M, when down, working in the groove, α , and extending out to the edge of the bed, A, as shown clearly in fig. 2.

Having thus described my invention, I claim as new, and desire to secure by Letters Patent—

The adjustable or rising and falling scrapers, M, and the fixed scrapers, G, arranged and applied to operate substantially in the manner as and for the purpose set forth.

G. D. JONES.
